SEAR-PIN CONTROL UNIT

Edward M. Claytor, Anderson, Ind., assignor to
General Motors Corporation, Detroit, Mich., a
corporation of Delaware

Application October 17, 1941, Serial No. 415,447

5 Claims. (Cl. 89—28)

This invention relates to an electrical apparatus for controlling the operation of a machine gun. Such apparatus includes a sear pin which is moved by an electromagnet.

It is an object of the invention to provide a sear pin control unit having means for the facile adjustment of the projected position of the sear pin beyond the mounting plate when moved by the electromagnet of the device without changing the normal position of the pin.

Further objects and advantages of the present invention will be apparent from the following description, reference being had to the accompanying drawing wherein a preferred embodiment of one form of the present invention is clearly shown.

In the drawing:

Fig. 1 is a plan view of the solenoid-operated sear-pin control unit constructed in accordance with the present invention;

Fig. 2 is a sectional view on the line 2—2 of Fig. 1;

Fig. 3 is a sectional view on the line 3—3 of Fig. 2.

In the drawing the numeral 20 designates a mounting plate of the usual construction adapted to be attached to a machine gun. Screws 21 secure to plate 20 a solenoid mounting plate 22 welded to a magnetizable shell 23 enclosing a solenoid coil 24 wound on a non-magnetizable tube 25 which surrounds a stationary core 26 projecting through the end of the shell 23 and through the plate 22 and providing a bearing for a sear-pin 27 threadedly connected with the solenoid armature 28 which slides in the tube 25. The lower end of the shell 23 is recessed at 30 to receive a magnetizable disc 31 centrally apertured to receive a magnetizable, threaded bushing 32. Disc 31 is retained by deforming portions of the lower edge of the shell 23, as indicated at 23a (Fig. 3). The magnet circuit of the solenoid includes the armature 28, 26, shell 23, disc 31 and bushing 32.

Bushing 32 is threadedly engaged by a nut 33 attached to a non-magnetizable plate 34 having a central aperture provided with flats 35 for receiving an extension 28a of the armature 28, said extension being provided with flats 28b engaging the flats 35 of disc 34 whereby the armature is connected with disc 34 for rotary movement therewith. Rotation of pin 27 is prevented by providing it with flats 27a engaging flats 27b provided by the mounting plate 20. A spring 36, located between the core 26 and armature 28, 55

urges the armature 28 downwardly against the disc 34 which serves as a stop to determine the normal position of the upper end of the pin 27 which is flush with the surface 20a of plate 20.

5 The extent to which the upper end of pin 27 moves above the surface 20a depends on the distance between the armature 28 and the core 26. When the solenoid coil 24 is connected with the current source the armature 28 is attracted upwardly, its movement being arrested when it strikes the core 26. The distance which the pin 27 moves upwardly from its normal position can be changed by changing the normal distance between the armature 28 and core 26. This distance is changed by applying a screw driver to the slotted lower end 28c of armature 28 and turning it. This causes the nut 33 to be screwed along the sleeve 32 and the armature 28 to be moved longitudinally. The nut 33 is retained in various positions of adjustment by virtue of engagement of a spring 37 with the flat surfaces of the octagonal periphery of the nut. One end of the spring 37 is coiled around stud 38 and the other end bears against a stud 39, said studs being attached to the disc 31. The turning of armature 28 to screw the nut along the sleeve 32 does not change the normal position of the pin 27 since the pitch of the threads connecting nut 33 with sleeve 32 is the same as the pitch of the threads connecting armature 28 with pin 27. If, for example, the nut 33 is screwed upwardly along the sleeve 32 by turning the armature 28 the armature 28 will be screwed upwardly along the pin 27 which can not rotate when the armature 28 is turned. In other words, when armature 28 is turned, the relative axial movement between nut 33 and sleeve 32 equals the relative axial movement between the armature 28 and the latch 27.

30 The lower end of shell 23 is provided with a shoulder 40 for receiving the flange 41 of a cover 42 having a tubular extension 43 which is threaded to receive a coupling for attaching a cable armor. Extension 43 encloses a connector 44 insulatingly supported by non-conducting disc 45 and connected with a clip 46 attached by screw 47 to a terminal stud 48 insulatingly supported by disc 31 and connected with one lead of coil 24, the other lead being grounded. Cover 42 is provided with hole 49 to permit access to screw 47 and with hole 50 through which the screw driver slotted extension 28a of the armature extends. Thus the distance which the latch 27 moves upwardly can be adjusted without removing cover 42. Cover 42 is secured to shell 23 by screws 51 extending

through the flat bottom wall of the cover and threadedly engaging tapped holes in disc 31.

While the form of embodiment of the present invention as herein disclosed constitutes a preferred form, it is to be understood that other forms might be adopted, all coming within the scope of the claims which follow.

What is claimed is as follows:

1. A sear-pin control unit comprising a mounting plate, a solenoid having a stationary core and a magnet winding and a movable armature supported by the plate, a sear-pin having a screw thread connection with the armature and extending through the mounting plate, means including portions of the mounting plate for preventing rotation of the pin, cooperating screw threaded members coaxial with the screw thread connection between the armature and pin, one of said members being rigidly fixed to the mounting plate and the other providing a stop for the armature, means operatively connecting the armature with the stop for rotation together and providing for axial movement of the armature relative to the stop, a spring disposed between the core and armature for urging the armature against the stop, the pitch of the screw threaded connection between said members being the same as the pitch of the screw thread connection between the armature and pin, whereby the turning of the armature stop member varies the gap between the armature and the core, while the normal position of the pin relative to the plate remains unchanged.

2. A sear-pin control unit comprising a base, a solenoid mounted on the base and comprising a coil, a core within the coil, a shell casing member, a sleeve fastened rigidly to said shell casing member, and an armature mounted on the base, a sear-pin having a threaded connection with the armature and extending through the base, means including portions of the mounting plate for preventing rotation of the sear-pin, an armature stop connected with the armature for rotation therewith and having a threaded connection with the sleeve, the pitch of the threads connecting the stop with the sleeve being the same as the pitch of the threads connecting the armature and pin, whereby turning the stop adjusts the gap between armature and core while the normal location of the pin remains the same, a spring disposed between the core and armature for urging the armature against the stop, a cover supported by the shell and having a hole coaxial the armature, and a screw-driver slotted part provided by the armature and accessible through said hole.

3. A sear-pin control unit comprising a base, a solenoid mounted on the base and comprising a coil, a core within the coil, a shell casing member, a sleeve fastened rigidly to said shell casing member, and an armature mounted on the base, a sear-pin having threaded connection with the armature and extending through the base, means

including portions of the base for preventing rotation of the sear-pin, an armature stop connected with the armature for rotation therewith and threadedly connected with the sleeve, the pitch of the threads connecting the stop with the sleeve being the same as the pitch of the threads connecting the armature and pin, whereby turning the stop adjusts the gap between armature and core while the normal location of the pin remains the same, a spring disposed between the core and armature for urging the armature against the stop, a cover supported by the shell and having a hole coaxial the armature, and a screw-driver slotted part provided by the armature and accessible through said hole, said screw-driver slotted part and the armature stop having cooperating means providing for the rotation of the armature and stop together while permitting axial movement of the armature relative to the core.

4. A sear-pin control unit comprising a base, a solenoid core surrounded by a coil and an armature mounted on the base, a housing for said solenoid members, a sear-pin screw having a screw threaded connection with the armature and extending through the base, means provided by the base for preventing rotation of the sear-pin, an armature stop screw having a screw threaded connection with the housing, the pitch of both of said screw-threaded connections being the same, means accessible through a hole in the housing for turning the armature, said armature turning means and said armature stop having cooperating means providing for the rotation of the armature and stop together while permitting axial movement of the armature relative to the core, whereby turning the armature adjusts the gap between armature and core while the normal location of the pin remains the same.

5. A sear-pin control unit comprising a base, a solenoid mounted on the base and comprising a coil, a core within the coil, a shell casing member, a sleeve fastened rigidly to said shell casing member, an armature slidably mounted within the sleeve and a spring disposed between the core and armature for urging the armature in one direction, a sear-pin having a screw thread connection with the armature and extending through the base, means including a non-round portion of the base for preventing rotation of the sear-pin; and a stop for the armature, said stop having a threaded connection with the sleeve and operatively connected with the armature for rotation therewith but permitting axial movement of the armature relative to the stop, the pitch of the threads connecting the stop with the sleeve being the same as the pitch of the threads connecting the armature and the pin, whereby turning of the stop adjusts the gap between the armature and core while the normal location of the pin relative to the base remains the same.

EDWARD M. CLAYTOR.
